FIG. 3

INVENTOR
G. Y. MCCLATCHIE

By *Wright & Clark*
ATTYS.

UNITED STATES PATENT OFFICE.

GRiffin Y. McCLATCHIE, OF PALO ALTO, CALIFORNIA.

AUTOMOBILE-ENGINE-OILING DEVICE.

1,387,654.

Specification of Letters Patent.

Patented Aug. 16, 1921.

Application filed July 26, 1920. Serial No. 399,035.

To all whom it may concern:

Be it known that I, GRIFFIN Y. McCLATCHIE, a citizen of the United States, residing at Palo Alto, in the county of Santa Clara and State of California, have invented new and useful Improvements in Automobile-Engine-Oiling Devices, of which the following is a specification.

This invention relates to improvements in automobile splash feed lubricating systems of the type wherein the bottom wall of the crank case is provided with shallow pockets or depressions arranged to provide pools of oil in the path of certain moving parts of the crank shaft or connecting rods, whereby said moving parts will distribute or "splash" the oil onto and lubricate various parts of the engine.

In systems of the character described, particularly in a well known and popular make of automobile, when negotiating grades, such as mountain roads and traveling on steep graded highways as well, or any road graded above 7%, the lower wall of the crank case is inclined so that most of the oil runs out of the shallow pockets or depressions and collects at the after end of the crank case. When this takes place, the small amount of oil retained in the pockets or depressions is insufficient to make pools large enough to permit the moving parts of the engine to encounter and "splash" the oil. Ordinarily, the parts of the engine which pick up or "splash" the oil are small and dip into the centers of the pools and as the pockets are relatively large, these small amounts of oil retained in the pockets as hereinbefore described are disposed at the rear portions of the pockets and will not be "dipped" by said moving parts. The result of this is that the engine fails to get the proper lubrication, will not operate properly, and begins to lose in power. Frequently, burned out or "scalded" cylinders and burned out bearings result from this lack of lubrication. It will, therefore, be apparent, that in mountainous sections of the country where grades of over 7% several miles in length are frequently encountered, the foregoing objections are most serious.

It is the primary object of this invention to provide simple, inexpensive, and easily installable means for overcoming the herein-noted objections and hazards attending the use of these "splash" feed systems, whereby

maximum power and engine efficiency may be obtained in negotiating mountain grades or roads graded above 7% or to an extent such that the difficulties before-mentioned regarding lubrication are brought about. To these ends, I provide upon the rear edges and sides of the pockets, walls or baffle plates extending above the level of the bottom of the crank case so as to increase the depth of the pockets whereby when the bottom wall is tilted, as in negotiating grades, sufficient oil will be retained in the pockets to permit the moving parts of the engine to dip into and "splash" the oil.

The invention possesses other advantages and features, some of which, with the foregoing, will be set forth at length in the following description wherein I shall outline in full that form of the invention which I have selected for illustration in the drawings accompanying and forming a part of the present specification. In said drawings, I have shown one form of the construction of my invention, but it is to be understood that I do not limit myself to such form since the invention as expressed in the claims may be embodied in a plurality of forms.

Referring to the drawings, Figure 1 is a fragmentary vertical sectional view taken through an automobile engine longitudinally, showing the same in position as it would appear when the automobile is negotiating a road graded above 7% and particularly illustrating the application of this invention to the engine.

Fig. 2 is a fragmentary plan view of the invention shown applied to the crank case.

Fig. 3 is a cross sectional view taken on the line 3—3 of Fig. 2.

Referring to the drawings, there is provided an engine 1 which is provided with a crank case 2 in which the crank shaft 3 and connecting rods 4 are operated. The lower ends of the connecting rods are provided with projecting portions or parts 5 which are adapted to contact with oil contained in the crank case so as to "splash" the oil and lubricate the various parts of the engine. The crank case 2 is provided with removable bottom section 6, in which section are formed a plurality of depressions providing pockets 7. These depressions or pockets 7 are disposed transversely of the bottom of the crank case and are adapted to contain shallow pools of oil so that the parts 5 of the engine will "dip" into said pools and

"splash" or distribute the oil to lubricate various parts of the engine. This construction is that ordinarily provided in a well known make of automobile. The sectional bottom 6 is secured by bolts 8 to the crank case 2, there being provided inside of the crank case, securing strips 9 which overlie the edges of the part of the crank case to which said member is bolted, the bolts extending through said strips 9.

In carrying out my invention, I mount upon the inside of the sectional bottom 6 of the crank case along the sides and rear edges of the pockets or depressions, walls or baffle members 10 and 11. These walls or members extend upwardly from the main portion of the sectional bottom, the walls 10 being along the rear edges of the pockets whereas the walls 11 are disposed at the sides of the pockets. As oil is fed into the crank case on the right side thereof and forwardly of the sectional bottom at substantially the point marked X, the securing strip 9 is cut away to provide a channel 12 adjacent to the oil feed point X. This allows the oil to flow readily to the removable bottom 6 and to enter the pockets 7. By having the walls 10 and 11 upon the sides and rear edges of the pockets only, the oil will readily enter the pockets at the front edges thereof. The sides of the pockets are spaced from the side edges of the sectional bottom and the side walls on the left side are likewise spaced, the latter sufficiently to provide channels 13 whereby part of the oil will run past the foremost pockets into the rear-most pockets.

Preferably the side walls 11 on the right side of the sectional bottom 6, this being the side in which the channel 12 is provided, are higher than the walls on the opposite side, the latter being of forwardly decreasing height. The ends of the side walls on the right side are turned outwardly so as to nearly engage the strip 9, as at 12'. This arrangement is provided so that as the oil enters the sectional bottom through the channel 12, the higher side walls will prevent the oil from running past the foremost pockets and will divert the oil into said pocket. The overflow from the pockets will take place on the opposite sides, over the lower walls 11. A discharge channel 14 is provided in the strip 9 adjacent to the rear

side thereof. Preferably, the walls 10 and 11 are formed of one piece of sheet metal bent into substantially U-shape and soldered or otherwise secured to the bottom 6, but these walls may be otherwise provided and formed as desired. The main purpose of the walls is to provide a means of obstruction for retarding the flow of oil out of the pockets when the automobile is running up hill and the bottom of the crank case is inclined. By this obstruction, sufficient oil will be retained in the pockets to provide pools of oil such as shown in Fig. 1 of the drawings, said pools being sufficiently deep to permit the parts 5 of the engine to dip into said pools and distribute the oil to various parts of the engine so as to properly lubricate the engine.

To prevent the running of oil past the channel 12 and outside of the strip 9, a small batch of waste or similar material 15 is placed under the strip 9 at the inner side of the channel. This provides an obstruction which will tend to divert the oil through the channel and onto the sectional bottom 6.

I claim:—

1. The combination with an automobile engine having a crank case and rotating parts of the engine in said crank case, there being pockets provided on the bottom wall of the crank case for the reception of pools of oil, into which pockets said rotating parts dip, of walls disposed along the sides and rear edges of said pockets to obstruct the flow of oil out of said pockets when said crank case is inclined forwardly and upwardly, the walls on one side of each pocket being substantially lower than on the opposite side.

2. The combination with an automobile having a crank case provided with depressions in the bottom wall thereof, a strip surrounding said depressions secured to and extending above said bottom wall, of means for feeding oil onto said bottom wall at a point in advance of said depressions and adjacent to one side of the bottom of said crank case, and walls mounted on the bottom of the crank case and extending along the side and rear edges of said pockets, certain of the walls on the side of the pockets having their forward ends turned outwardly to substantially engage said strip.

GRIFFIN Y. McCLATCHIE.
